 N. Y., a corporation of New Jersey

Application February 29, 1936, Serial No. 66,425

21 Claims. (Cl. 254—172)

This invention is for a hoist operated by fluid under pressure.

An important object of the invention is to provide a pressure fluid operated hoist of exceedingly simple and yet compact rugged structure.

Another important object of this invention is to provide a pressure fluid operated motor hoist in combination with means whereby the speed of rotation of the hoist may be simply and effectively controlled.

A further object of this invention is to provide in a mechanism of this type automatically acting means for changing the speed of rotation of the hoist as the load thereon varies.

These and other objects are successfully attained by means of the invention herein disclosed.

This invention resides substantially in the combination, construction, arrangement and relative location of parts as will be described in detail below.

This application is a continuation in part of my copending application Serial No. 42,571 filed September 28, 1935.

In the drawings,

Figure 1 is an elevational view with some parts in cross section of one form of pressure fluid operated hoist in accordance with this invention;

Figure 2 is a left-hand elevational view thereof;

Figure 3 is a view taken on the plane 3—3 of Figure 1 with the cover plate removed and the shaft shown in section;

Figure 4 is a cross sectional view taken on the line 4—4 of Figure 1;

Figure 5 is an end elevational view of the mechanism of Figure 1 from the right-hand end showing the modification of means for automatically controlling the speed of operation of the hoist with changes in loads;

Figure 6 is a cross sectional view on the line 6—6 of Figure 7 showing a modified form of automatically operated speed control means;

Figure 7 is a cross sectional view taken on the line 7—7 of Figure 6;

Figure 8 is an end elevational view from the left hand end of the engine employing the automatic control means of Figures 6 and 7; and

Figure 9 is a longitudinal cross sectional view through the main shaft showing in diagrammatic perspective form the relative positioning of the gears and passages with respect to the main shaft.

This invention involves a hoist comprising a pressure fluid operated engine having a fixed shaft and an outer rotatable casing in the form of a cable drum. The pressure fluid engine portion of the hoist is so constructed that the speed of rotation of the engine housing, i. e., the cable drum, may be either manually or automatically changed without employing complicated auxiliary mechanism. It is often desirable and in many cases necessary in employing pressure fluid engines to move the cable at a slow speed when under load and at a high speed when unloaded, i. e., with empty hook.

It is common practice in the commercial use of pressure fluid engines to limit the rate of flow of pressure fluid being pumped to the engine to a range of 6 to 10 feet per second. An engine in accordance with this invention designed to have an output of 25 H. P. and employing a pressure fluid at 500 lbs. per square inch will lift a load of 7500 pounds at 110 feet per minute when supplied with the pressure fluid at the rate of 90 gallons per minute. It is desirable, however, when the hook is empty to take in or pay out the cable at from 600-700 feet per minute. If the cable is moved at 600 feet per minute the engine would require 540 gallons of pressure fluid per minute. The auxiliary equipment necessary to meet this wide range of gallonage would be expensive and complicated.

The general object of this invention is to provide an engine which may be readily and simply controlled by a manually operated device whereby for the same gallonage per minute of pressure fluid supplied to the engine it may be operated in either direction under load at, for example, 110 feet per minute and with an empty hook at 600-700 feet per minute. An example of this type of service would be on board an airplane carrier, where the hoist would be employed to raise airplanes from the surface of the ocean to the deck of the carrier. With the motor of this invention the empty hook can be raised or lowered at high speed and raised or lowered at low speed.

In addition to providing the engine with manual control, this invention may include, where such is desirable, automatic control of the engine speed with changes in load. For example, if an airplane is being raised from the surface of the ocean to deck level and a wave suddenly raises the airplane, the automatic control under the reduction in load goes into action to speed the engine up, thereby taking up the resulting cable slack. As soon as the cable again goes under

tension, the automatic control returns the engine to slow, load-lifting speed.

The mechanism by means of which these objects are secured will now be described in detail.

- 5 The engine is shown comprising a pair of standards 1 and 2, in which is mounted a hollow shaft 3. This shaft, in the form of device illustrated in Figures 1 to 4 inclusive, is locked in the standards so that it cannot turn. The right hand end of 10 the shaft, as shown in Figure 9, is sealed by means of a bored tapped plug 3' in which the pressure fluid supply pipe S' is secured. The other end of the shaft is closed by means of a cap member 3'' and has a threaded bore therein 15 in which is secured the pressure fluid exhaust pipe E'.

Mounted on the shaft between the standards are a number of ball bearing assemblies 4 on which the motor housing which forms the cable drum 20 rotates. This housing comprises a central cylindrical portion 5, the outer surface 6 of which forms the cable drum. The central portion of the housing is integral with the hollow heads 7 and 8 which are closed at the ends by means of the 25 cover plates 9 and 10. The packing gland assemblies 11 and 12 are provided to prevent fluid leakage at the points where the shaft issues from the ends of the housing. Secured within the head formed by the portions 7 and 9 of the housing is an internal or ring gear 13 which is secured therein by a series of screws 14. In a similar way another internal or ring gear 15 is secured in the portion 8-10 of the housing by means of the machine screws 16. Mounted on each side of the 30 ring gear 13 in the manner shown are the plates 17 and 18 which fit around the ring gear and form a sealed housing therefor. Likewise the ring gear 15 is surrounded by the plates 19 and 20. Mounted between the plates 17 and 18 are a series 35 of short shafts 21 which are locked between the plates, as is clear from Figure 1. Referring to Figures 3 and 4, it will be seen that there are six of these shafts mounted between the plates 17 and 18. Journaled on roller bearings on the 40 shafts are the spur gears 22 which mesh with the teeth of the ring gear 13. In the space between these gears is the filler plate 23, the shape of which will be seen from Figure 3. As will be seen from Figure 3, this filler plate 23 fills in all the 45 space around the spur gears 22 and fits snugly up against the teeth of the ring gear 13 between the spur gears. The spur gears have a close running fit with the circular notches in the filler plate and the ring gear has a similar fit with the periphery thereof between the notches. The construction of the parts in the head 8-10 is the same. A series 50 of shafts (not shown) extends between the plates 19 and 20 and have spur gears 24 thereon which mesh with the ring gear 15. A filler plate 25 is employed in this assembly which has the same shape as the filler plate 23. The plates 17 and 18 and the filler plate 23 are all keyed to the fixed 55 shaft 3 so that they may not rotate thereon (Figure 1). Similarly, the plates 19 and 20 and the filler plate 25 of the other part of the motor are likewise keyed to the shaft 3. It will then be noted that when the motor casing revolves on the bearings 4 to function as a drum it carries 60 with it the ring gears 13 and 15. The other parts all remain stationary. Figure 9 shows the relative arrangement of the ring and spur gears of the two sets. The filler plates have been omitted in this view.

75 As is shown in Figure 9, a control valve is slid-

ably mounted within the hollow shaft 3. This control valve comprises a central cylindrical portion 26 having a bore 27 extending from one end towards and terminating near the other end. In other words, the right hand end Figure 9 of bore 27 is closed. As is shown in Figure 9, this bore 27 issues from the left hand end of the sleeve 26. Mounted on one end of the sleeve 26 are a series of flutes 28 around the periphery of the sleeve 26 and spaced from each other as shown. Mounted on the sleeve adjacent the flutes 28, longitudinally spaced therefrom, is another series of flutes 29 which are circumferentially staggered with respect to the flutes 28. Towards the other end of the sleeve 26, but spaced 15 in therefrom a short distance, is another series of flutes 30. Mounted on the extreme end of the sleeve adjacent thereto is a cylindrical piece 31 which forms a sort of cap for the sleeve but which has a bore so that the passage 27 of the sleeve 20 opens therethrough.

The sets of flutes 28, 29, 30 and cap 31 have an external diameter which is such as to form a tight sliding fit with the interior of the shaft 3. These members form slide bearing members for 25 the sleeve 26 and with it comprise a control valve by means of which the pressure fluid supply to the engine may be controlled. It may be noted that the slide valve assembly may be machined from a solid piece of material or built up or made 30 in any other way apparent to those skilled in the art.

Each of the flutes 28, of which there are six, has a pair of passages 28^a and 28^b therethrough into the passage 27. All of the passages 28^a are circumferentially aligned as are all of the passages 28^b. Each of the flutes 29 (of which there are six) has a passage 29^a therethrough into the passage 27 and all of which are circumferentially aligned. Each of the flutes 30, of which there 40 are six, has a pair of passages 30^a and 30^b therethrough into passage 27. The group of passages 30^a are circumferentially aligned as are the passages 30^b. The cap 31 has two diametrically arranged slots 31^a which do not open into passage 45 27 and four holes 31^b opening into passage 27. The slots 31^a and holes 31^b are circumferentially aligned.

Mounted on the end cap 3'' of the shaft 3 is a small cylinder 32 in which the piston 33 is 50 mounted. This piston is connected by means of the piston rod 34 to the slide valve as shown in Figure 9. At 35 is a four way control valve. The pipe 36 of this valve is an exhaust pipe and the pipe 39 is a pressure fluid supply pipe. Pipe 37 connects one end of cylinder 32 with the valve 35 and pipe 38 connects the other end with the valve 35. When the valve is in the position shown in Figure 9, the pressure fluid is supplied from the source through pipe 39, valve 35 and 60 pipe 38 to cylinder 32, exerting a pressure on the right hand face of piston 33 so as to move it to the position shown, carrying with it the slide valve assembly within the shaft 3. When the valve 35 is manipulated to its other position, pipe 65 39 is connected to pipe 37 and pipe 38 is connected to pipe 36, whereby pressure is exerted on the left hand face of piston 33 moving it to the extreme right and carrying the slide valve assembly with it.

The plate 17 is provided with six passages extending radially thereof and uniformly spaced in a circumferential direction around the disc. In a like manner, a similar set of six passages are formed in the plate 18. In making these plates 75

they may be bored inwardly from the outer circumference and the outer ends of the bores plugged as indicated in the drawings. Four of the passages 40 in the plate 17 and four of the 5 passages 41 in the plate 18 are of the same diameter. Two of the passages 40^a in the plate 17 and two of the passages 41^a in the plate 18 are of larger diameter than the corresponding 10 passages 40 and 41. In the other plates 19 and 20 there are provided in each six equally spaced 15 passages, all of the same smaller diameter, like passages 40, 41 in the plates 17 and 18. Figure 3 shows the relative relationship between these 20 passages. The passages 40 in the plates 17 and 19 are in the same angular position and fall in Figure 3 in line with each other. In other words the passages 40 of the plate 19 lie directly in back of the passages 40 of the plate 17, and similarly the passages 41 of the plate 20 lie directly 25 in back of the passages 41 in the plate 18. The 30 passages 40 and 41 of the plates 19 and 20 corresponding to the large passages 40^a and 41^a are also in alignment, but, being smaller, show up in Figure 3. The relative arrangement of the 35 different sets of passages is illustrated in Figure 9. These passages have been shown diagrammatically in Figure 9 by dash and dot lines to show the relative positioning thereof. They, of course, only exist as bores in the various plates 40 in accordance with the foregoing description.

As partly indicated in Figure 4, the various plates are mounted upon the shaft 3 so that the 45 passages 40, 41, 40^a and 41^a are in radial alignment with the short passages in the shaft 3. 50 Several of these short passages have been indicated at 3^a in Figure 4. It is likewise to be noted that the short passages are of the same diameter as the longer passages with which they cooperate. This is apparent from Figure 4. Figure 4 also indicates that each of the passages 40 and 40^a opens to two of the gears 22 at one side 55 thereof (see also Figure 9). The passages 41 and 41^a likewise open to these gears on the other side thereof. The points where these sets of passages open to the same gears are circumferentially spaced, as is clear from the different figures.

When the slide valve is in the position shown in Figure 9, the passages 28^a and 30^a are in alignment with the passages 3^a, see Figure 4, in the shaft 3, and of course, with the six passages 41. The 60 passages in the shaft 3 in alignment with the six passages 40 in the right hand portion of the engine open into the shaft 3 between the sets of flutes 28 and 29 (see Figure 9). Passages 28^b and 29^a are blanked off until the slide valve is moved to the right, Figure 9. When this occurs 65 passages 41 are open to passages 28^b and passages 40 are open to passages 29^a. Thus when piston 33 moves the slide valve to the right all of 70 passages 40 and 41 of the right hand portion of the engine are connected to passage 27.

The construction of the left hand portion of the engine is generally similar but differs in some 75 details therefrom. The passages 30^a, when the slide valve is in the position shown, are in alignment with the passages 3^a and the passages 41 in alignment with both. At this time the 80 passages 40 and 40^a of the left hand portion of the engine open into shaft 3 through passages 3^a formed in the shaft. These passages 3^a open 85 into the shaft between the flutes 30 and the cap 31. The cap 31 is shown with a pair of notches 31^a which are circumferentially aligned with the 90 passages 3^a corresponding to the passages 40^a. Thus when the slide valve moves to the right

these two passages remain open to the interior of shaft 3. At this time passages 40 open into 95 passage 27 through the passages 31^b. The flutes 30 are provided with two large passages 30^b which pass therethrough and open into the passage 27 in the sleeve 26. When the slide valve is moved to the right these passages 30^b line up with the passages 3^a in the shaft 3 which are in alignment with the passages 41^a. At this time 100 all the passages 41 open into passage 27 through the small passages 30^b.

Thus with the slide valve to the right all the 105 passages 40, 41 and 41^a open into passage 27 and the two passages 40^a open into shaft 3.

The main fluid pressure pipe S and the main 110 exhaust pipe E may be connected either to the pipes S' and E', or to E' and S' respectively by the four-way valve 300.

The operation of this engine will now be described in detail. It is first to be assumed that 115 pressure fluid from any suitable supply source is connected to pipe S, so as to supply the pressure fluid at a pressure of for example 500 pounds per square inch, and at some practical rate of flow per second. It is also to be assumed that 120 valve 35 is in the position shown in Figure 9, so that piston 33 has positioned the slide valve to the position shown in that figure. It is also to be assumed that the four-way valve 300 is in the position shown in Figure 9. Pressure fluid 125 will then flow from the source through pipe S, valve 300, pipe S', cap 3' into shaft 3 at the right hand end. It will then flow through shaft 3 between the flutes 28, 29 and 30. The fluid 130 will enter all of the passages 40 since they are open to the space between the flutes 28 and 29 and 30 and the cap 31, and to passages 40^a since they are open to the space between the flutes 30 and the cap member 31. Fluid pressure will 135 therefore be supplied to all of the gears to cause them to rotate in the direction of the arrows marked in Figure 9. The fluid will discharge through all of the passages 41 and 41^a into the passage 27 since they are all connected thereto. The fluid may then discharge from the left hand 140 end of passage 27 into pipe E' and through valve 300 to the main discharge pipe E. Under these 145 conditions the cable drum which is connected to the ring gears 13 and 15 will revolve in the direction of the arrows applied to the ring gears in Figure 9, and the engine will be operating at slow speed, and for example under an assumed condition to move the cable at 110 feet per minute under a load of 7,500 pounds.

When the cable hook is not loaded the engine 150 may be speeded up to reel the cable at about 600 feet per minute by moving the slide valve to the right. This is accomplished by manipulating valve 35 so that the pressure fluid is supplied to the left hand face of piston 33 forcing 155 the slide valve to the right to a position where all of the passages 40 and 41 open into the passage 27 leaving only passages 40^a open to the space between the shaft 3 and the slide valve 26. Under these conditions and with valve 300 in the 160 position shown in Figure 9, the pressure fluid will only be supplied to the two large passages 40^a and to the gears associated therewith. The pressure fluid which is discharged from these two gears 165 will enter passage 27 through the two large discharge passages 41^a. All of the other passages are open to the passage 27 so that the fluid is free to circulate therethrough under no pressure. Under these conditions the gears will operate 170

ate at a much faster rate causing the cable drum to revolve at a higher speed.

The previously described low and high speed operation of the cable drum in a reverse direction 5 may be effected by simply operating the main control valve 300 to its other position so that pipe S is connected to pipe E' and pipe E is connected to pipe S'. With this setting of valve 300 and with the slide valve 26 in the position 10 shown in Figure 9, the engine will operate at slow speed in the reverse direction. Under these circumstances fluid under pressure will flow from the source through pipe S, valve 300, pipe E' into shaft 3 and passage 27. From this passage 15 it will flow to all of the gears through pipes 41 and 41^a and be discharged from all of the pipes 40 and 40^a to the space between the slide valve and shaft 3. It may then travel through pipe S', valve 300, and pipe E to exhaust or waste. 20 To operate the engine at high speed in this reverse direction slide valve 26 is moved to the right hand position, as previously described, by manipulating valve 35. In this case valve 300 will remain in its last named position so that the pressure fluid is supplied to all of the passages 25 40, 41 and 41^a. The two large passages 40^a are open to exhaust into the space surrounding the slide valve. Under these conditions the engine will operate at high speed in reverse direction 30 and the only fluid that will be exhausted to pipe S' will be that discharging through the passages 40^a. All of the other passages are connected together with the space 27 so that the fluid will be free to circulate therethrough in a closed circulatory path similar to the action that occurs for the original direction of rotation and high speed operation. In the first case that is with direction of rotation as indicated in Figure 9 the passage 27 at no pressure, while in the second instance for high speed operation the fluid will similarly circulate but under pressure.

Several modifications will now be described in which the operation of the slide valve is automatic and under the control of the load of the engine. In the modification shown in Figure 5, the standard 2 is provided with a yoke 52 mounted thereon and supporting a pair of adjustable set screws 53 arranged to limit the oscillatory movement of a lever 50. This lever is mounted upon and attached by means of the key 51 to the shaft 3. In this case the shaft 3 is free to turn in the standards 1 and 2 but is limited in its turning movement by the set screws 53 co-acting with the arm 50. The outer end of the lever 50 is provided with a curved rack 56 which meshes with a gear 57 mounted upon the valve stem of the valve 35. This valve is the same as the valve 35 of the previous engine. Valve 35 is supported upon a bracket 55 and is connected 60 to the cylinder 32 by the pipes 37 and 38 as before, and provided with the pressure fluid supply pipe 39 and exhaust pipe 36. The end of arm 50 is connected to the bracket 55 by means of a coil spring 54, as shown.

It will be assumed, by way of example, that the hoist is being employed to raise an airplane or boat off the water and is under load with the drum 6 rotating in a clockwise direction, Figure 5. Under these conditions shaft 3 will rotate in a 70 counterclockwise direction, Figure 5, carrying lever 50 with it until it engages the lower stop screw 53. Shaft 3 will be given a slight angular rotation as limited by the stops 53 in a counterclockwise direction by reason of the reaction of

the fluid pressure forces which cause rotation of the drum on the shaft. As will be readily apparent, the force which tends to cause clockwise rotation of the drum 6 must react against something and in the particular mechanism disclosed this reaction will be upon the shaft 3 through the gears secured thereto. Rack 56 engaging pinion 57 will move valve 35 to the position shown in Figure 9. If a wave reduces the load on the cable sufficiently by pushing upward on the airplane or boat, spring 54 will pull arm 50 upwardly, operating valve 35 to the reverse position so that piston 33 will move the slide valve to its other position. The engine will then immediately speed up by reason of the cutting out of the 15 smaller passages, as previously described. The slide valve 26 does not have any rotative movement with respect to shaft 3 during the operations described above but rotates with it as do all the parts mounted upon and connected with 20 the shaft.

As soon as the cable goes under tension again arm 50 will shift downwardly, tensioning spring 54 and resetting valve 35. This will result in a return of the slide valve to the position shown in 25 Figure 9.

The mechanism of Figures 6, 7 and 8 will now be described. In function it is similar to that of Figure 5, but is structurally different. In this arrangement the shaft 3 is again free to rotate 30 in the standards 1 and 2 but its rotative movement, however, is confined between close limits as before by means of the yoke 52, mounted on the standard 2, and the adjustable stop screws 53, which cooperate with the lever 60 (see Figure 8), 35 which lever is similar to the lever 50 keyed to the shaft 3. A heavy coil spring 58 connects the arm of lever 60 with a fixed bracket or standard 61.

The control valve for this mechanism is mounted on the opposite end of shaft 3 and is arranged 40 so that the movable portion of the valve also forms the cylinder for the piston 33 which operates the slide valve. The control valve is mounted upon a bracket 63 supported from the standard 1. This bracket terminates in a ring-shaped 45 casing 66 formed with the chambers 66' and 68 to which the exhaust and supply pipes 67 and 69 respectively are connected. The movable portion of the valve is shown at 65 in the form of a cylindrical body having a central chamber in 50 which the piston 33 operates. Bolted or otherwise secured to the movable valve member 65 are the side plates 64 which fit on opposite sides of the ring-like terminal 66 of arm 63. Thus the parts 65 and 64 are secured together and attached 55 to the end of shaft 3, as is clear from Figure 7. When shaft 3 oscillates, limited by arm 60, the parts 65 and 64 rotate with it. The manner of forming a tight sliding joint between these parts and the ring member 66 is shown in Figure 7. The movable valve member 65 is provided with four passages 74, 75, 76 and 77, radiating outwardly from the piston cylinder to the periphery. The ring member 66 is provided with four ports, numbered 70 and 71, opening into the chamber 66', and 72 and 73, opening into the chamber 68. Referring to Figure 7, the piston 33 is in a position corresponding to that of Figure 9 where the slide valve is positioned to operate the engine at slow speed. In this case lever 60 moves downwardly, engaging the lower stop 53 and tensioning spring 58. This positions valve member 65 to the position shown in Figures 6 and 7 so that pressure fluid may flow from pipe 69 in the chamber 68 through passages 73 and 71 into the cylinder 75

der of piston 33 to exert pressure on the right hand face of the piston. This holds the slide valve in a position corresponding to that of Figure 9. When the load is reduced or released 5 on the drum, spring 58 pulls lever 60 upwardly, carrying shaft 3 with it, and valve member 65 is thus moved to the position where passage 76 communicates with passage 72 and passage 75 communicates with passage 71. Passages 74 and 77 10 are moved out of alignment with the passages 70 and 73. Fluid then flows from pipe 69 and chamber 68 through passages 72 and 76 to the left hand face of piston 33, causing it to move to the right. The pressure fluid in the right hand end of the 15 cylinder is exhausted through passages 75 and 71 into chamber 66' and from thence through pipe 67. As soon as the load goes on again the valve is repositioned to move piston 33 to the left, carrying the slide valve with it.

20 The principle of speed change in fluid engines or pumps as herein described is not limited to use in a geared engine or pump but may equally well be employed in movable vane and piston engines or pumps.

25 From the above description it will be apparent that the features comprising the novel combination of this invention may be incorporated in other physical forms without departing from the true novelty thereof. I do not, therefore, desire 30 to be strictly limited to the specification and drawings as here presented for purposes of illustrating the new combination, but rather to the invention as it has been set forth in the following claims.

35 What I seek to secure by United States Letters Patent is:

1. A fluid pressure engine as described, comprising a fixed shaft, a casing rotatably mounted on the shaft, a plurality of cooperating gears mounted on the shaft and casing, means forming 40 passages for supplying fluid pressure to and exhausting it from said gears whereby the casing may be rotated on said shaft, and means for completely closing off some of said supply and 45 exhaust passages whereby the speed of rotation of the casing may be changed.

2. In a fluid pressure engine, a shaft, a casing journaled on the shaft, a plurality of intermeshing gear elements respectively connected to said

50 shaft and casing, means for supplying the fluid under pressure to and exhausting it from said gear elements to effect relative rotation between the casing and shaft, and means subject to variations in the load on the motor for changing the 55 speed of rotation thereof.

3. In a fluid pressure engine, a shaft, a casing journaled on the shaft, a plurality of intermeshing gear elements respectively connected to said shaft and casing, means for supplying the fluid under pressure to and exhausting it from said gear elements to effect relative rotation between the casing and shaft, and means subject to variations in the load on the motor for cutting out a plurality of the supply and exhaust passages to change the speed of rotation thereof.

70 4. In a pressure fluid operated engine, the combination comprising a relatively rotatable shaft and casing, a ring gear mounted in said casing, a cage mounted on the shaft, a plurality of spur gears rotatably mounted on said shaft cage and meshing with said ring gear, a supply and exhaust passage for each spur gear, and valve means for cutting out some of said supply and exhaust passages whereby for a constant supply of pres-

sure fluid the speed of rotation of the engine may be varied.

5. In a pressure fluid operated engine, the combination comprising a relatively rotatable shaft and casing, a ring gear mounted in said casing, a cage mounted on said shaft, a plurality of spur gears rotatably mounted on said cage and meshing with said ring gear, a supply and exhaust passage for each spur gear in said cage, and means including a valve subject to variations in load on the engine for cutting in and out of use a plurality of said supply and exhaust passages, whereby the speed of rotation of the engine may be automatically varied. 5 10

6. In a pressure fluid operated engine, the combination comprising a fixed shaft, a casing journaled on said shaft, a ring gear secured in said casing, a plurality of spur gears rotatably supported by said shaft and meshing with said ring gear, means forming a supply and exhaust passage for each spur gear, and valve means for cutting in and out of use some of said supply and exhaust passages, whereby the speed of rotation of the casing on the shaft for a constant supply of pressure fluid may be varied. 15 20 25

7. A pressure fluid operated engine comprising a fixed shaft, a casing mounted for rotation on said shaft, a pair of ring gears mounted in said casing, a plurality of spur gears meshing with each of said ring gears, means for rotatably supporting said spur gears from said shaft, said means having a supply and exhaust passage for each of said spur gears, and valve means for controlling said supply and exhaust passages whereby a plurality of said spur gears may be cut in or out of circuit to vary the speed of rotation of the casing.

8. A variable speed pressure fluid operated engine including a fixed hollow shaft, a casing rotatably mounted on the shaft, a ring gear secured in said casing, a plurality of spur gears meshing with said ring gear, means mounted on said shaft for rotatably supporting the spur gears and formed with a supply and exhaust passage for each spur gear, a valve mounted in said shaft, and means for positioning said valve to cut in or out of circuit a plurality of said passages whereby with a constant rate of feed of fluid pressure the speed of the engine may be varied.

9. A variable speed pressure fluid operated engine including a fixed hollow shaft, a casing rotatably mounted on the shaft, a ring gear secured in said casing, a plurality of spur gears meshing with said ring gear, means mounted on said shaft for rotatably supporting the spur gears and formed with a supply and exhaust passage for each spur gear, a valve mounted in said shaft, and pressure fluid operated means for positioning said valve to cut in or out of circuit a plurality of said passages whereby with a constant rate of feed of fluid pressure the speed of the engine may be varied. 50 55 60

10. A variable speed pressure fluid operated engine including a hollow shaft, a casing rotatably mounted on the shaft, a ring gear secured in said casing, a plurality of spur gears meshing with said ring gear, means mounted on said shaft for rotatably supporting the spur gears, said means forming a supply and exhaust passage for each spur gear, a valve mounted in said shaft, and pressure fluid operated means controlled by and in accordance with variations in the load on the engine for positioning said valve to cut in or out of circuit a plurality of said pas- 70 75

sages to change the speed of rotation of the engine.

11. A fluid pressure engine comprising a hollow shaft and casing journaled for relative rotation, a ring gear on the casing, a plurality of spur gears meshing with the ring gear, means for rotatably supporting said spur gears and formed to provide fluid supply and exhaust passages, a valve slidably mounted in said shaft, and fluid pressure operated means for positioning said valve to cut in and out of circuit a plurality of passages.

12. A hoist motor of the type described comprising a fixed hollow shaft, a casing mounted on said shaft for rotation and forming a cable drum, a pair of ring gears secured within said casing, two pairs of spaced supporting plates secured to said shaft, a plurality of spur gears journaled between each of said pairs of plates and meshing with the adjacent ring gears, said plates being formed with supply and exhaust passages, one of each for each spur gear, passages in said shaft in alignment with said supply and exhaust passages, and a slide valve mounted in said shaft and provided with means to control said supply and exhaust passages whereby a plurality of them may be cut in and out of circuit.

13. A hoist motor of the type described comprising a hollow shaft, a casing mounted on said shaft for rotation and forming a cable drum, a pair of ring gears secured within said casing, two pairs of spaced supporting plates secured to said shaft, a plurality of spur gears journaled between each of said pairs of plates and meshing with the adjacent ring gears, said plates being formed with supply and exhaust passages, one of each for each spur gear, passages in said shaft in alignment with said supply and exhaust passages, a slide valve mounted in said shaft and provided with means to control said supply and exhaust passages whereby a plurality of them may be cut in and out of circuit, and means actuated by and in accordance with variation in the load on the engine for shifting said valve.

14. A fluid pressure hoist engine comprising a fixed hollow shaft, a casing journaled for rotation on said shaft and forming a cable drum, a pair of ring gears secured within said casing, inner housings surrounding each of said ring gears and secured to said shaft, a plurality of spur gears journaled in each of said inner housings and meshing with the adjacent ring gears, said inner housings being formed with a plurality of pairs of passages comprising a supply and an exhaust passage for each spur gear, said shaft having passages therethrough in alignment with all of said passages, the supply and exhaust passages for several of said spur gears in one of said inner housings being larger than the others, and a slide valve mounted within said shaft and provided with means to cut in and out of circuit all of said smaller passages while leaving the larger passages always in circuit.

15. A fluid pressure hoist engine comprising a fixed hollow shaft, a casing journaled for rotation on said shaft and forming a cable drum, a pair of ring gears secured within said casing, inner housings surrounding each of said ring gears and secured to said shaft, a plurality of spur gears journaled in each of said inner housings and meshing with the adjacent ring gears, said inner housings having a plurality of pairs of passages comprising a supply and an exhaust passage for each spur gear, said shaft having

passages therethrough in alignment with all of said passages, the supply and exhaust passages for several of said spur gears in one of said inner housings being larger than the others, a slide valve mounted within said shaft and positionable to cut in and out of circuit all of said smaller passages while leaving the larger passages always in circuit, and pressure fluid operated means for positioning said valve.

16. A fluid pressure hoist engine comprising a hollow shaft, a casing journaled for rotation on said shaft and forming a cable drum, a pair of ring gears secured within said casing, inner housings surrounding each of said ring gears and secured to said shaft, a plurality of spur gears journaled in each of said inner housings and meshing with the adjacent ring gears, said inner housings having a plurality of pairs of passages comprising a supply and an exhaust passage for each spur gear, said shaft having passages therethrough in alignment with all of said passages, the supply and exhaust passages for several of said spur gears in one of said inner housings being larger than the others, a slide valve mounted within said shaft and positionable to cut in and out of circuit all of said smaller passages while leaving the larger passages always in circuit, and means controlled by and in accordance with variations in load on the engine for positioning said valve.

17. A fluid pressure hoist engine comprising a hollow shaft, a casing journaled for rotation on said shaft and forming a cable drum, a pair of ring gears secured within said casing, inner housings surrounding each of said ring gears and secured to said shaft, a plurality of spur gears journaled in each of said inner housings and meshing with the adjacent ring gears, said inner housings having a plurality of pairs of passages comprising a supply and an exhaust passage for each spur gear, said shaft having passages therethrough in alignment with all of said passages, the supply and exhaust passages for several of said spur gears in one of said inner housings being larger than the others, a slide valve mounted within said shaft and positionable to cut in and out of circuit all of said smaller passages while leaving the larger passages always in circuit, and fluid pressure operated means actuated by and in accordance with variations in the load on the engine for positioning said valve.

18. A pressure fluid operated hoist engine comprising a shaft, means for supporting the shaft so that it may oscillate through a small angle, a casing journaled for rotation on said shaft, a ring gear mounted in said casing, a pair of spaced plates supported on said shaft and enclosing said ring gears, a plurality of spur gears journaled between said plates, said plates having a plurality of pairs of passages, each pair in turn comprising a supply and exhaust passage for each spur gear, said shaft being hollow and having passages through a wall thereof in alignment with said passages, a slide valve mounted in said hollow shaft for cutting some of said passages in and out of circuit, means for limiting oscillation of said shaft, and means controlled by the oscillation of said shaft by and in accordance with variations in the load on the engine for positioning said valve.

19. In a fluid pressure engine, a shaft, a casing journaled on the shaft, a plurality of relatively movable elements respectively connected to the shaft and casing, means for supplying fluid under pressure to and exhausting it from said elements

to effect relative rotation between the casing and shaft including a plurality of passages, and manually operated valve means for sealing off some of the supply and exhaust passages whereby for a constant supply of pressure fluid the speed of rotation of the engine may be varied.

20. In a fluid pressure engine, a shaft, a casing journaled on the shaft, a plurality of relatively movable elements respectively connected to the shaft and casing, means for supplying fluid under pressure to and exhausting it from said elements to effect relative rotation between the casing and shaft including a plurality of passages, and automatically operated valve means for cutting out some of said supply and exhaust passages whereby

for a constant supply of pressure fluid the speed of rotation of the engine may be varied.

21. In a fluid pressure engine, a shaft, a casing mounted on the shaft whereby relative rotation therebetween may occur, a plurality of relatively movable elements respectively connected to the shaft and casing, means for supplying fluid under pressure to and exhausting it from said elements to effect relative rotation between the casing and shaft, and means operated by and in accordance with variations in the load on the engine for cutting in and out of use a plurality of said supply and exhaust passages whereby the speed of rotation of the engine may be automatically varied.

PRESTON WHITCOMB. 15
